UNITED STATES PATENT OFFICE.

CHARLES H. KNOBBS, OF PHILADELPHIA, PENNSYLVANIA.

PRIMING-CUP.

1,390,139.

Specification of Letters Patent. Patented Sept. 6, 1921.

Application filed September 19, 1919. Serial No. 324,837.

To all whom it may concern:

Be it known that I, CHARLES H. KNOBBS, a citizen of the United States, residing at Philadelphia, in the county of Philadelphia 5 and State of Pennsylvania, have invented new and useful Improvements in Priming-Cups, of which the following is a specification.

An object of the invention is to provide a 10 cup particularly adapted for internal combustion motors, for priming the cylinders thereof with a fuel or for injecting into the cylinders, scavenging fluids or the like for the removal of carbon deposits from the interior of the cylinders, whereby the mentioned operations can be carried out while the motor is in operation or in non-operating 15 position.

Among other features the invention comprehends various improvements over the 20 usual forms of priming cups now generally used on motors such as internal combustion engines, and in which, in the prevalent present forms of devices, the priming of the cylinders without danger of a back-flare, can only be accomplished when the motor is not 25 running. With my device the cylinders can be primed or scavenging fluid injected into the cylinders whether the motor is running 30 or not, it being desirable, however, particularly in cases where the motor is to be scavenged, that the scavenging fluid be injected into the cylinders, while the motor is in operation. To accomplish this result I provide a 35 chamber, forming a part of the cup and which has an inlet and an outlet separately controlled as to the opening and closing thereof so that while the motor is running and the outlet of the chamber closed, the 40 fluid to be injected into the cylinders can be received through the open inlet into the chamber and the inlet then closed and the outlet subsequently opened, permitting the 45 fluid to be injected into the cylinders and carried away with the succeeding explosions of the gases therein without danger of the 50 explosions or back-flare passing through the chamber and injuring the operator who is or has injected the fluid.

55 In the further disclosure of the invention, reference is to be had to the accompanying drawings constituting a part of this specification, in which similar characters of reference denote corresponding parts in all the views, and in which,

Figure 1— is a fragmentary side elevation

showing my device applied to the cylinder of an internal combustion engine, parts being broken away to disclose the underlying structure, with the outlet of the chamber 60 shown in closed position and the inlet in open position.

Fig. 2— is a vertical sectional view taken through the device showing the outlet open and the inlet closed.

Fig. 3— is a plan view of the structure as shown in Fig. 1.

Fig. 4— is a horizontal sectional view taken substantially on the line 4—4 in Fig. 2, and

Fig. 5— is a fragmentary side elevation showing the means for limiting the opening and closing movement of the cap.

Referring more particularly to the views, the cylinder of an internal combustion engine 75 is indicated by the numeral 10 and my form of cup, indicated by the numeral 11, is applied to the top or head 12 of the cylinder. The cup 11 comprises a casing 13 formed to provide an inner chamber 14 having an outlet 15 communicating by a longitudinal bore or passage 16 with the cylinder 10, said bore being formed in a stem 17 integral with the casing 13 and threaded into the head 12 of the cylinder as shown. The outlet 15 is 80 formed to provide a valve seat 18 for the lower end of a needle valve 19, the stem 20 of which has threaded engagement with the casing at 21 and provided with an external handle 22 whereby rotation of the valve in 85 one direction will raise it from the valve seat 18 and rotation in the other direction will bring the valve into engagement with the valve seat to close the outlet. The casing 13 is formed with an upstanding tubular projection 23 exteriorly threaded and which in fact provides a packing gland for a packing 90 95 100 105 110 24 encircling the stem 20 of the handle valve with a packing ring 25 disposed above and on top of the packing 24 and also loosely encircling the stem 20 of the needle valve 19.

A cap 26 is threaded onto the projection or packing gland wall 23 as shown, and the cap is provided with an inlet passage 27 which in the rotation of the cap on the casing can be brought into or out of registration with an inlet passage 28 of the casing, affording communication with the chamber 14. Similarly the cap 26 has an air passage 29 which will be brought into registration with an air passage 30 in the casing 13 when the passages 27, 28 are in registration so that when a fluid

is poured into the chamber through the passages 27, 28, the air can seep out through the registering passages 29, 30.

The cap is provided with an external handle 31 for rotating the cap on the casing and when the cap is screwed down, it will be seen that the cap will compress the packing 24 around the stem 20 of the needle valve so as to prevent any leakage at this point. A gasket 32 is arranged between the casing and cap and is of course provided with openings 33, 34, which register with the openings 28, 30, the casing having a circular stepped down portion providing a ledge over which fits an annular extension 37 of the cap, thus further preventing leakage and also facilitating the proper seating of the cap relative to the casing in the operation of the device.

In the use of the device described I will assume that the needle valve is in closed position; that the motor is in operation and that it is desired to scavenge the cylinder with a suitable carbon removing fluid, such as kerosene or the like. Operation of the handle 31 will rotate the cap 26 upon the casing, bringing the passages 27, 29, into registration with the passages 28, 30 and the fluid is now poured in through the passages 27, 28 to flow into the chamber 14 while the air in the chamber displaced by the incoming fluid will pass out through the passages 29, 30. The handle 31 is now actuated to rotate the cap to move the registering openings 27, 29, out of registration with the passages 28, 30, thus sealing the fluid in the chamber 14 and when this has been accomplished the lever or handle 22 is actuated to unseat the needle valve 19 so that the suction created in the cylinder will draw or suck the fluid contained in the chamber, downwardly through the bore 16 into the cylinder where the said fluid will of course be operated upon and exploded or taken up to perform its function. Of course it will be understood that the device can be employed in the usual manner as the ordinary priming cup when the motor is not running, but it will be apparent that with my form of device the scavenging operation taking place while the motor is running and which is the most desirable time for the ac-

complishment thereof, prevents the flame from the explosion, from shooting out through the bore 16 and chamber 14 into 55 the face of the operator for the reason that the cap is moved into closed position before the needle valve is unseated. It may be that in certain cases it is desired to scavenge the cylinder by allowing the explosion to pass 60 out through the priming cup and in an instance of this character, the cap is moved into open position so that the openings 27, 28 and 29, 30, register with the needle valve, unseated to provide a free passage from the 65 cylinder to the exterior.

In order to prevent accidental unthreading of the cap 26 I preferably have the side wall 37 of the cap formed with a cut out portion, a screw 39 being threaded into the 70 side of the casing 13 on the exterior to lie in the path of the cut out portion and which cut out portion provides stop flanges 40 whereby in rotating the cap the same will only have a limited movement in one direction or the other, which limited movement however is sufficient for the rotation of the cap to bring the passages 27, 28, and 29, 30, into or out of registration, as desired.

Having described my invention, I claim— 80

A priming cup comprising a casing formed at its bottom with a reduced extension threaded for engagement within a threaded hole in the cylinder head of an engine, said extension being formed with a bore leading into a valve seat at its juncture with the casing, a threaded extension at the top of the casing having a central threaded opening, and an inlet port and a small passage formed in said last named extension 85 near the side thereof, a cap upon said upper extension and having a handle whereby it may be rotated, said cap having a port and a passage adapted to register with the first named port and passage, a valve normally 90 closing said seat and having a stem threaded through the threaded opening in the upper extension of the casing and passing revolvably through the cap, and a handle at the upper end of said stem.

In testimony whereof I affix my signature.

CHARLES H. KNOBBS.
